CURTAIN FOR MOTOR-VEHICLES.

1,266,990.

Specification of Letters Patent. Patented May 21, 1918.

Application filed November 2, 1916. Serial No. 129,063

To all whom it may concern:

Be it known that we, KARL F. RANGER and LOUIS M. SPENCER, both citizens of the United States, and residing at Detroit, in the county of Wayne and State of Michigan, and Highland Park, in the county of Wayne and State of Michigan, have invented a new and Improved Curtain for Motor-Vehicles, of which the following is a specification.

10 Side curtains for motor vehicles are now usually supported by buttons whereby they are attached to the longitudinal bow or associated member of the top. As is well known, this construction is objectionable because it interferes with the occupants in getting into or leaving the vehicle. The usual custom is to unbutton the curtain from its support sufficiently to allow it to be bent up about a line joining the opposite upper and lower corners, a mode of procedure that requires time and stooping and also carries with it liability of contact with the wet curtain in case it is raining. Numerous efforts have been made to avoid these 15 difficulties but they have, in turn, involved other objections such as expense and encroachment on the space within the interior of the car.

One type of these improvements consists 20 in a pocket formed in upper face of the door at a point near the free edge thereof, together with a post, or other supporting structure, that rises substantially to the lower edge of the longitudinal bow of the top, and has the curtain fastened thereto so that, when the door is swung outwardly, the post and curtain are carried with it. This construction is expensive, cannot be sold in the market as an accessory which is 25 applicable to substantially all cars (particularly because of the defacing of the door which is necessary in its installation), and, when arranged close enough to the longitudinal bow to prevent rain from beating in, does not allow the necessary vibration of the bow in a vertical plane.

With these considerations in mind the nature of the present invention will be understood; it consists in a motor vehicle body 30 having a door opening, a door swinging therein, and a collapsible top for the body, together with a curtain for the space between the upper edge of the door and the top, and means carried solely by the top for supporting the upper edge of the curtain

above the door, said supporting means being capable of swinging outwardly with the curtain and of supporting the latter throughout the swinging movement. The invention further consists in a curtain supporting means of the character stated which is adapted to be readily attached to bows of various cross sections such as are found in cars of different makers; in a support that may be attached to or detached from the top without the use of tools and without defacing the bow; in pivot means whereby the curtain support is frictionally prevented from undesirable swinging; in holding means for the free end portion of the curtain support; and in the various details of construction shown, described and claimed.

In the drawings, Figure 1 is a side elevation of a motor vehicle showing an adaptation of the invention to a well known form of body and top. Fig. 2 is a fragmentary side view, parts being broken away showing a preferred construction of the curtain support. Fig. 2^a is a section on the line 2^a—2^a of Fig. 2. Fig. 3 is a transverse section at one side of the vehicle showing the means for retaining the end of the curtain supporting arm in position on the bow. Fig. 4 is a perspective view of the arm retaining means. Fig. 5 is a fragmentary section through the curtain supporting arm and a portion of the curtain. Fig. 6 is a side view, parts being broken away, showing the curtain support applied to an inclined longitudinal bow. Figs. 7 and 8 are similar views illustrating additional modifications. Fig. 9 is a part-section part-elevation showing a modified pivot construction for the curtain arm. Fig. 10 is a view taken from the right hand side of Fig. 9.

Like reference characters refer to like parts.

The car shown in Fig. 1 includes the body 1 having a collapsible top which comprises the bows 2, the longitudinal bow 3, Fig. 2 (that, in practice, is made sectional and varies considerably in cross-section both in shape and size in cars of different makers), and the fabric cover 4. The front portion of the bow 3 rests on, or is attached to, the wind shield 5. Suitable pivots 6 and 7, located at their rear edges, are provided for the doors 8 and 9, but it will be understood that the pivots may be located along the front

edges of the doors in either or both instances. As shown, the spaces between the front door and the bow and between the rear door and the bow are closed, respectively, 5 by curtains 11 and 12, the former of which preferably extends back to the forward edge of the rear door, and, while the curtain 12 is shown terminating in line with the pivots 7, it might extend farther rearwardly. Also 10 one or both curtains might extend beyond the free edge of the corresponding door. The construction thus far described is well known.

At points substantially in line with the 15 pivots for the doors, members 15 (Fig. 3), preferably of pressed sheet metal, each of which includes two out-turned contact points 16 (that may be formed as end portions of diverging arms 18) are hooked over the 20 bow 3 from the inside of the car. The lower ends of the members are turned laterally at substantially right angles toward the outside of the car, as indicated at 19, to constitute seats for the cylindrical ends 25 20 of curtain supporting arms 21 which are bent upwardly at 22 into close relation to the bow. Both the ends 20 of the arms and the portions 19 of the hooked members are centrally perforated to receive the pivot 30 rod 23 that has at its upper end a shoe 24 which is held firmly in engagement with the lower face of the bow 3 by a strong coil spring 25, the lower end of which bears upon the upper face of the perforated sheet metal 35 disk or washer 26; the disk in turn bears upon the upper surface of the end 20 and holds the latter closely to the seat 19, thereby aligning the curtain support with the bow, and at the same time establishing a predetermined 40 frictional resistance to the swinging of the arm (which may be varied by using springs of different strengths) and also entirely preventing rattling. If desired, the elements 19 and 26 may be provided 45 respectively with flanges 28 and 29 whereby a close relative alinement of the parts with the axis of the pivot rod 23 is insured without the necessity for accurate work in the formation of the perforations.

For convenience a hand grip 30 is secured to the lower end of the pivot whereby the 50 spring may be compressed to allow the device to be attached or released.

The curtain support may obviously be 55 readily attached to bows which vary from one another to a considerable degree, both in shape and size, and maintains the curtain in substantially the plane of the door throughout the swinging movement of the latter, it being understood that the lower edge of the curtain is secured to the door by buttons 32 or otherwise. Such portions of the curtain as may extend to one side of the door opening are supported by buttons 60 65 or other fastenings 33-34 (Fig. 2). As

shown in Fig. 5, the curtains already provided for the car may be used by passing a loop 35 of fabric of a length substantially equal to the width of the door over the arm 21 and stitching the upper edge of the usual 70 curtain thereto.

In order to retain the free end of the rods 21 in the closed position, a holding means, best shown in Figs. 2, 3 and 4, is provided, but the details of the device may be varied 75 within wide limits. This device comprises two stamped metal members 36 and 37 including finger grips 38 and 39 which receive the ends of a strong flat spring 40—the latter being passed around a pivot 41 where- 80 by the members are joined. These members are curved to conform to the upper and lower surfaces of the bow 3, and it is preferred to arrange the pivot 41 at about the upper level thereof so that the movement of 85 the member 37 relatively to the member 36 most effectually accommodates itself to different sizes of bows. Spring clips 42 and 43, forming parts of the member 36, flare outwardly from the lower edge of the bow 90 to form a pocket wherein the end of the arm 21 is firmly held. If desired the clips 42 and 43 may be so shaped as to allow the arm to be withdrawn without force other than that applied to the door to open the 95 latter, as is obvious. The holder thus formed may be readily attached to or detached from the bow, does not rattle, holds the rod 21 securely, and is inexpensive.

If desired, the free vertical edge of the 100 curtain may be stiffened by a small tube 45 (Figs. 2 and 2^e) having its upper end split and clamped around the tube 21 by means of the screw 46; the tube 45 extends down nearly to the door and may be secured 105 to the curtain by a fabric loop 48 suitably sewed thereon. When the door is swung open the tube will cause the curtain to align more accurately therewith and also tends to prevent flapping.

In the embodiment shown in Fig. 6, the longitudinal bow 50, which corresponds to the bow 3, is inclined in a well known manner. The curtain arm is supported for pivotal movement at a point in line with the pivots 6 of the door 8 by means designated 51 as a whole similar to that heretofore described, and the free end of the arm is likewise retained by holding means 52. The curtain 11 may extend to the rear of 120 the pivots 6 but in any event is buttoned at 53 to the top and is secured to the free end of the arm in any desired manner (not shown); therefore the entire curtain swings out with the arm as before.

The embodiment shown in Fig. 8 differs from that just described in that the portion of the curtain 11 above the bow 50 is replaced by a three-cornered curtain 54 that is fastened to the top and to the bow in any 130

suitable manner. When the curtain 54 is removed or partly unbuttoned, ventilation may take place through the opening.

Referring to Fig. 7, the door 58 is mounted on pivots 59 at its forward edge and the curtain 54 extends from the rear edge of the door to the wind shield 5. The pivotal supporting means 60 for the curtain arm 61 is mounted on the bow 50 in line with the pivots 59, while the arm itself passes rearwardly and downwardly along the under side of the bow to a point near the rear edge of the curtain, where it is held by a retaining means 63 similar to that hereinbefore described. From the retaining means the arm is curved upwardly to the upper rear corner of the curtain 64 and is fastened thereto in any suitable way. In this as in all other cases where the curtain 20 extends beyond the pivotal axis, it bends about that axis in an obvious manner as the door swings.

Figs. 9 and 10 show a modified construction of arm support in which it will be noted that the pivot 65 is threaded and provided with a nut 66 slotted at 68 to receive a cotter pin 69 whereby an initial adjustment to correspond to the size of the bow 3 is obtained. Mounted on the pivot 30 is a rotatable cam 70 having a flat lower surface and an upper surface having oppositely disposed depressions 71 and elevations 72 (preferably 90° apart), the latter also having slight central depressions 73. A shallow corrugated spring washer 74 is interposed between the upper face of the portion 20 of the arm and the lower face of the cam; consequently when the nut is properly adjusted and the cam is swung by the handle 75 into the position shown, the washer is forced down upon the arm to hold it in alignment beneath the bow and the depressions 73 of the cam are held in close relation to the shoe 24.

The construction may be varied widely from the forms described and we do not, therefore, wish to be limited except as indicated by the subjoined claims.

We claim:—

1. In combination with a bow of a motor vehicle top, a curtain arm, a side curtain supported by said arm, and means for supporting said arm for pivotal movements about a substantially vertical axis, said means comprising a member arranged to engage the bow, and means entirely external to the bow for holding the member in engagement therewith.

2. In combination with a motor vehicle having a top, a side curtain structure pivoted to swing in respect to said top, said structure including a curtain supporting arm pivotally supported at one end, and detachable means carried by the top for normally holding the free end of the arm,

said detachable means including a pair of members arranged to exert pressure on the top, and resilient means tending to urge said members into pressure exerting relation to the top.

3. In combination with a motor vehicle having a collapsible top, a side curtain structure pivoted to swing in respect to said top, said structure including a curtain supporting arm pivotally supported at one end, and detachable means carried by the top and constructed and arranged to normally resiliently support the free end of the arm to prevent movement in all directions.

4. In combination with a collapsible top of a motor vehicle, said top including a longitudinal bow of curved cross-section, a side curtain supporting arm, and means for supporting the arm on the bow to allow swinging about a vertical axis, said means comprising a hook-like member engaging over the curved upper surface of the bow, said means also comprising a second member movable toward and from the lower surface of the bow, whereby bows of different sizes may be accommodated and the hook like member may be prevented from becoming accidentally detached.

5. In combination with a bow of a collapsible top of a motor vehicle, a curtain supporting arm swingable in and out in respect to said bow, means for supporting the arm on the bow, said means comprising a bow receiving clamp including a spring pressed jaw.

6. In combination with the bow of a collapsible top of a motor vehicle, a curtain supporting arm pivoted to swing in and out in respect to said bow, means independent of the pivot for normally supporting the free end of said arm from the bow, said means including a bow gripping clamp having a spring pressed jaw.

7. In combination with the bow of a vehicle top and a curtain supporting arm swingable in respect to the bow about a vertical axis, said arm having a cylindrical head, a member arranged to coact with the bow, said member forming a seat for the lower side of the head, a second member arranged to coact with the bow and having a contact portion pressing thereon, said second member including a cylindrical portion that passes through the head and the first member on the line of the pivotal axis of the curtain arm, and a resilient member interposed between the contact portion of the second member and the head.

8. In combination with the bow of a vehicle top and a curtain supporting arm swingable in respect to the bow about a vertical axis, said arm having a cylindrical head and a body portion, a clamping member coacting with the bow and forming a seat for the lower end of the head, and

means interposed between the head and the bow for forcing the head down onto the seat.

9. In combination with the bow of a vehicle top and a curtain supporting arm swingable in respect to the bow about a vertical axis, said arm having a cylindrical head and a body portion, a clamping member coacting with the bow and forming a seat for the lower end of the head, and means interposed between the head and the bow for forcing the head down onto the seat, the body portion of the bow being bent upwardly from the head and continued along close to the lower side of the bow.

10. In combination with the bow of a vehicle top and a curtain supporting arm swingable in respect thereto about a vertical axis intersecting the bow, said arm including a shallow cylindrical head and a body portion, pivot means for supporting the arm from the bow, said means including two members each arranged to press on a corresponding end surface of the cylindrical head and forming between them a slot through which the body portion of the arm may swing, one of the members having a flange surrounding the curved face of the cylinder and conforming thereto, and means for pressing the members tightly together upon the head.

11. In combination with a vehicle including a longitudinal bow and a covering extending along the outer side of said bow and from thence upwardly, a curtain supporting arm mounted to swing in respect to the bow about a substantially vertical axis, means for supporting the arm on the bow, said means including a clamp having contact portions embracing the upper and lower surfaces of the bow, and means passing along the inner side of the bow for connecting the contact portions.

12. In combination with a motor vehicle having a collapsible top including a longitudinally extending bow, a curtain arm, a side curtain supported by said arm, and means for supporting said arm for pivotal movements about a substantially vertical axis, said means including an element ar-

ranged to exert pressure on the bow, and a resilient member tending to urge the element into pressure exerting relation to the bow.

13. In combination with a motor vehicle having a collapsible top including a longitudinally extending bow, a curtain arm, a side curtain supported by said arm, and means for supporting said arm for pivotal movements about a substantially vertical axis, said means including two members, one arranged to exert pressure on the top side of the bow and the other arranged to exert pressure on the lower side of the bow, and a resilient member tending to force the two members into pressure exerting relation to the bow.

14. In combination with a motor vehicle having a collapsible top including a longitudinally extending bow, a curtain arm, a side curtain supported by said arm, and means for supporting said arm for pivotal movements about a substantially vertical axis, said means including two members, one arranged to exert pressure on the top side of the bow at points spaced longitudinally thereof and the other arranged to exert pressure on the lower side of the bow at a point disposed longitudinally between the above mentioned points, and a resilient member tending to force the two members into pressure exerting relation to the bow.

15. A motor vehicle having a top, detachable pivot means secured thereto, a curtain arm pivoted to swing on said pivot means, and resilient means tending to both hold said pivot means to the top and to impose a resistance to the swinging movement of the arm.

16. In combination with a motor vehicle body, a top therefor, a curtain suspended wholly from the top, and a stiffening element extending down along one edge of the curtain and being free to rise and fall in respect to the adjacent edge of the body, whereby free relative vibration of the stiffening element in respect to the body is allowed.

KARL F. RANGER.
